United States Patent Office

Des. 197,212
Patented Dec. 31, 1963

197,212

KNOB

La Verne E. Clayton, Rockford, Ill., assignor to Amerock Corporation, Rockford, Ill., a corporation of Illinois

Filed May 17, 1963, Ser. No. 74,940

Term of patent 14 years

(Cl. D10—8)

FIGURE 1 is a front elevational view of a knob embodying my new design.

FIG. 2 is a side elevational view of the knob as viewed from the left in FIG. 1.

FIG. 3 is a top plan view of the knob.

FIG. 4 is a sectional view taken along the line 4—4 in FIG. 1.

FIG. 5 is a sectional view taken along the line 5—5 in FIG. 1.

FIG. 6 is a sectional view taken along the line 6—6 in FIG. 1.

FIG. 7 is a sectional view taken along the line 7—7 in FIG. 4.

I claim:

The ornamental design for a knob, substantially as shown.
